US00D432331S

United States Patent [19]

Podgorney et al.

[11] Patent Number: Des. 432,331

[45] Date of Patent:  Oct. 24, 2000

[54] CABINET

[75] Inventors: Gerald J. Podgorney, St. Louis; Roger H. Decker, St. Peters, both of Mo.; Kurt Botsai, Thousand Oaks, Calif.; Cary Chow, Venice, Calif.; Juan Cilia, Thousand Oaks, Calif.; Chris Glupker, Van Nuys, Calif.; Ravi Sawhney, Calabasas, Calif.; Frank Zinni, Capistrano Beach, Calif.

[73] Assignee: Crane Co., Stamford, Conn.

[] Term: 14 Years

[21] Appl. No.: 29/107,969

[22] Filed: Jul. 16, 1999

[51] LOC (7) Cl. 06-04

[52] U.S. Cl. D6/445

[58] Field of Search D6/432-448; D18/3.1; D20/1, 4, 5; 312/109, 114, 138.1, 198, 204, 223.1, 223.2

[57] CLAIM

The ornamental design for a cabinet, as shown and described.

DESCRIPTION

FIG. 1 is a perspective view of a cabinet showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The bottom of the cabinet forms no part of the claimed design.

The broken lines shown in FIGS. 1 and 6 are for illustrative purposes only and form no part of the claimed design.

1 Claim, 6 Drawing Sheets
